W. F. GRUPE,
WEAVING APPARATUS,
APPLICATION FILED JUNE 19, 1919.

1.385,444.

Patented July 26, 1921.

William F. Grupe ^{Inventor}
By his Attorney
Henry J. Luecke

UNITED STATES PATENT OFFICE.

WILLIAM F. GRUPE, OF HUDSON HEIGHTS, NEW JERSEY.

WEAVING APPARATUS.

1,385,444.

Specification of Letters Patent. Patented July 26, 1921.

Application filed June 19, 1919. Serial No. 305,370.

To all whom it may concern:

Be it known that I, WILLIAM F. GRUPE, a citizen of the United States of America, residing at Hudson Heights, county of Bergen, 5 State of New Jersey, have invented certain new and useful Improvements in Weaving Apparatus, of which the following is a specification.

This invention relates to weaving apparatus and particularly to the harness and shafts of weaving apparatus.

More particularly, the invention relates to harness comprising heddles, eyes having an open side and means coacting to close the 15 open side of the heddle. In the more preferred forms of the invention, means are provided for guiding and maintaining the effective portions of the heddles in substantially a common plane.

20 Further features and objects of the invention will be more fully understood from the following description and accompanying drawings, in which—

Figure 1 is a front vertical elevation of a 25 shaft and harness comprising my invention;

Fig. 2 is an end vertical elevation; and

Fig. 3 is a sectional elevation on line 3—3 of Fig. 1.

Referring to the drawings, the embodiment of the invention shown therein is of 30 the type adapted to be supported by suspension from a single shaft 1, although the invention, as will appear, is applicable for other types of harness and shafts.

35 Each heddle 2 is provided with the eye 3 having an open side 4. Preferably, each heddle 2 is formed of flat wire or plate of metal or other suitable material, the eye 3 being formed by filing or milling or otherwise, to provide a substantially rectangular form of eye. The heddle 2 may be suspended by the cord 5 from the shaft 1, and for such 40 purpose, I have shown the terminal portion 6 of the cord 5 looped about the shaft 1 and 45 suitably tied as at 7.

Means are provided for guiding and maintaining the heddles in a substantially common plane, as by a slotted frame, the heddles being disposed in the slot thereof, and 50 side by side. In the particular embodiment indicated in the drawings, I have shown two sets or groups of heddles arranged alternately in substantially a common plane, and guided in reciprocating movement in such 55 plane by the slotted upper guiding member

8 and a similar slotted lower guiding member 9, the slots of which are disposed substantially in the common plane of reciprocation of the sets of heddles. Preferably, each heddle 2 of one set is provided with the 60 uppermost laterally extending portion 10, projecting in one direction, while each heddle 11 of the other set is provided with a similar laterally extending portion 12 projecting in another direction, to which is attached the cord 13, similar to cord 5, and extending about the other shaft 14.

For other number of sets of heddles, the arrangement of such sets of heddles in the desired common plane or planes is similar 70 and the number of shafts conform to the number of the sets of heddles.

Such upper and lower slotted frame members may be coupled as a unit by the side cords or bars 15. The slotted frame is suspended from any suitable fixed support such as a bar or the like by means of the side cords or bars 17. For the purpose of holding the slotted frame in vertical alinement, the weights 18 may be employed as by suspending the same by the cords 19 from the lower slotted member 9.

For simplicity of attachment of the operating means 5, 13, to the respective heddles 10, 11, of the respective sets, each heddle may be recessed as by the provision of the perforations 20.

Thus, upon reciprocation of the shafts 1, 14, the corresponding sets of heddles are reciprocated within the guiding frame 8, 9, 90 the guiding frame being held in relatively fixed position, whereby all heddles are reciprocated in substantially a common plane. It will be further noted that the open sided eyes of the respective sets are maintained closed during the stage of reciprocation of the heddles. Preferably, each slotted frame member 8, 9, is formed of similar outside flat bars 21, 22, held spaced apart by means of the end spacing blocks 23, each such 95 block 23 being held in position by means of the removable bolt 24 having a head 25 at one end and the removable nut 26 at the opposite end.

Upon completion of the weaving operation, the warp threads are withdrawn from the open sided eyes 3 and the frame members 8, 9 removed by opening the bolts 24 and separating the respective frame bar members 21, 22, while leaving the warp 110

thread intact. The ready withdrawal of the warp threads from the heddles and the removability of the heddles and the guiding frame from the warp threads, is advantageous in the weaving of an endless belt, whereby the weaving may be continued until but a relatively small remainder of the warp threads is remaining or unwoven, whereupon removal of the heddles and the guiding frame, the remaining weft threads may be woven for the remaining length of the warp threads.

In general, the invention is also applicable in all weaving operations for weaving with a given number of sets of heddles until a certain stage is reached, then withdrawing the warp threads from such sets of heddles and, if desired, substituting the different set of heddles and continuing the weaving under the replaced conditions, as desired.

Whereas I have described my invention by reference to specific forms thereof, it will be understood that many changes and modifications may be made without departing from the spirit of the invention, as defined by the appended claims.

I claim.

1. Weaving apparatus comprising a set of heddles, each heddle being formed of relatively stiff material, a lateral side of each heddle being provided with an eye having an open side, slotted guide means for said heddles, said heddles being disposed laterally side by side, means for supporting and operating said heddles, and means disposed laterally of each heddle for effectively closing

the open side of its eye and means for supporting said closing means.

2. Weaving apparatus comprising a set of heddles, each heddle being formed of relatively stiff material, a lateral side of each heddle being provided with an eye having an open side, slotted guide means for said heddles, said heddles being disposed laterally side by side, means for separately supporting and separately operating said plurality of sets of heddles respectively, and means disposed laterally of each heddle for effectively closing the open side of its eye and means for supporting said closing means.

3. Weaving apparatus comprising a set of heddles, each heddle being formed of relatively stiff material, a lateral side of each heddle being provided with an eye having an open side, slotted guide means for said heddles, said heddles being disposed laterally side by side, means for separately supporting and separately operating said plurality of sets of heddles respectively, said supporting means comprising lugs projecting in one direction from the respective heddles of one set and lugs projecting in a transverse direction from the respective heddles of another set, and means disposed laterally of each heddle for effectively closing the open side of its eye and means for supporting said closing means.

In testimony whereof I have signed this specification this 29th day of May, 1919.

WILLIAM F. GRUPE
